SEPARATING CIRCUIT

Randall C. Ballard, Audubon, N. J., assignor to
Radio Corporation of America, a corporation of
Delaware

Application April 4, 1939, Serial No. 265,923

4 Claims. (Cl. 178—7.3)

My invention relates to television receivers and particularly to circuits for separating synchronizing pulses from picture signals.

In present day television systems, it is the practice to transmit a composite signal consisting of picture signals and synchronizing pulses as described in British Patent No. 448,065. At the receiver it is desired that the synchronizing pulses be separated from the picture signals and that these pulses only be applied to the horizontal and vertical deflecting circuits. Various circuits for obtaining this separation have been proposed but, in practice, good separation has been difficult to obtain because of variations in amplitude of the incoming signal. This difficulty could be overcome by utilizing an automatic volume control circuit having a sufficiently flat characteristic but the use of such a circuit would be unduly expensive.

Accordingly, an object of my invention is to provide an improved circuit for separating synchronizing pulses from picture signals.

It is a further object of my invention to provide an improved means for obtaining complete separation of synchronizing pulses from picture signals regardless of wide variations in the amplitude of the signal impressed upon the separating means.

In a preferred embodiment of my invention, I employ two synchronizing impulse-separating circuits connected in cascade through an amplifier, the circuit design being such that the first separating circuit functions only as an amplifier for signals of low amplitude while complete separation is effected by the second separating circuit. For signals of comparatively high amplitude, however, the first separating circuit effects partial separation and prevents overloading or saturation of the amplifier connecting the two separating circuits whereby the synchronizing pulses are not removed from the signal reaching the second separating circuit.

The invention will be better understood from the following description taken in connection with the accompanying drawings in which

Figure 1 is a circuit diagram of one preferred embodiment of my invention,

Figure 2 is a circuit diagram of another embodiment of my invention,

Figures 3 and 4 are diagrams showing the operation of my circuit for incoming signals of low amplitude,

Figures 5 and 6 are diagrams showing the operation of my circuit for incoming signals of high amplitude, and

Figure 7 is a diagram which is referred to in explaining the operation of my improved separating circuit.

Referring to Fig. 1, there is shown a portion of a television receiver embodying one preferred form of my separating circuit. The video signal comprising picture signals and synchronizing pulses appears in the output circuit of a second detector indicated at 10 and is supplied over a conductor 11 to the video amplifier and cathode ray tube and over a conductor 12 to the separating circuit.

The separating circuit comprises a first separating tube 13, an amplifier tube 14 and a second separating tube 16. In this particular embodiment, the two separating circuits are of the same type, each one having synchronizing impulses of positive polarity impressed thereon and being biased by means of a flow of grid current. A separating circuit of this type is described and claimed in Patent No. 2,207,839, issued July 16, 1940, in the name of W. A. Tolson and assigned to the Radio Corporation of America.

Considering the separating tube 13, it may be a triode as illustrated or it may be of a type including more grids such as a pentode. Signal is supplied to the grid 17 of the tube 13 through a grid condenser 18. A grid leak resistor 19 is provided having sufficient resistance to prevent the grid condenser 18 from discharging a very substantial amount between the occurrence of successive frame frequency synchronizing pulses.

Preferably a lower than normal plate voltage is applied to the plate 21 of the tube 13 to cause plate current cut-off to occur at a less negative grid voltage than would otherwise.

The output of the tube 13 is applied to the amplifier tube 14 through a coupling condenser 22. A grid leak resistor 23 is provided for the tube 14 which preferably has such resistance that the time constant of the circuit including it and the condenser 22 is less than the time constant of the preceding circuit comprising grid condenser 18 and resistor 19 for a reason which will be explained later.

Preferably, normal plate voltage is applied to the plate of tube 14. While this tube is shown with zero bias, actually there is a negative bias on the grid during operation due to a grid leak biasing action. As will appear hereinafter, the amplifier tube 14 need not be of a type which will take a wide grid voltage swing without distortion but may be the same type tube as the tube 13, for example.

The second separating circuit in the circuit

illustrated is of the same type as the separating circuit described above. The synchronizing pulses appear in the plate circuit of amplifier 14 with a positive polarity and are impressed upon the grid 26 of tube 16 through a grid condenser 27. A grid leak resistor 28 is given sufficient resistance to make the grid condenser 27 hold over most of its charge between successive frame synchronizing pulses. At the same time, its resistance is such that the time constant of the circuit including it and the condenser 27 is less than the time constant of the corresponding circuit for the preceding tube. Thus, from the input to the output of the complete separating circuit the time constant of the grid condenser-grid leak resistor circuit is decreasing in value.

The voltage applied to the plate 31 of tube 16 preferably is below rated voltage but may be higher than the voltage applied to the plate of the first separator tube.

The operation of the circuit will be apparent from the following discussion of the circuit action under two conditions, first, for an incoming signal of small amplitude, and, second, for an incoming signal of large amplitude.

Referring to Fig. 3, the grid voltage-path current characteristic of the tube 13 is shown at 31. An incoming signal of comparatively small amplitude is shown at 32-33, the picture signal portion being indicated at 32 and the line synchronizing pulses being indicated at 33. It will be apparent that under these conditions the tube 13 is acting as an amplifier, its output being indicated at 32a-33a. Its output is further amplified by the tube 14 whereby a signal of large enough amplitude for good separation appears on the grid of the second separator tube 16 as shown in Fig. 4.

In Fig. 4, the grid voltage-plate current characteristic of the tube 16 is shown at 34. The input signal 32-33 has sufficient amplitude to cause only the synchronizing pulses to appear in the plate circuit of the tube 16 as indicated at 33a.

From an inspection of Figs. 3 and 4, it will be seen that the grid bias of a separating tube increases with an increase in the amplitude of the applied signal as described in the above-mentioned Tolson application whereby there is good separation at the second separating tube although there is either little or no separation at the first separating tube under the condition assumed.

Now considering the second condition of operation where the amplitude of the incoming signal is large, reference will be made to Figs. 5 and 6.

Referring to Fig. 5, it will be seen that the signal 32-33 of increased amplitude has caused the bias on the grid of separator tube 13 to increase. Partial separation of synchronizing pulses and picture signals occurs, the signal appearing in the plate circuit of the tube 13 being as shown at 32a-33a.

The output of tube 13 is amplified by tube 14 and applied to the separator tube as shown in Fig. 6. Complete separation is provided by this second separating circuit as shown at 33a-33a.

From the foregoing, the importance of applying signals of substantial amplitude to a separating circuit for obtaining good separation will be appreciated. It might appear at first glance that satisfactory separation would be obtained by employing an ordinary amplifier in

place of the first separating circuit. This is not the case, as will be evident from an inspection of Fig. 7, where the grid voltage-plate current characteristic of the amplifier tube 14 is shown at 36. It is assumed that an incoming signal 32-33 of large amplitude has been applied to the grid of tube 14 without any separating action in a preceding tube. Obviously, some or all of the synchronizing pulses will be clipped or wiped off and the resulting signal 32a appearing in the plate circuit of the tube 14 will be worthless for synchronizing purposes.

On the other hand, by practicing my invention, the signal applied to the tube 14 under the conditions just assumed is the signal 32a-33a (Fig. 3). It is apparent that this signal 32a-33a may readily be amplified by an amplifier tube such as the tube 14 without distortion or clipping of the synchronizing pulses.

20 The difficulty illustrated by Fig. 7 could be avoided by employing a tube designed to give an undistorted output with a wide voltage swing on its grid. This, however, would be attained with lower amplification and thus insufficient signal would be available on weak input signals.

In Fig. 1 certain circuit and voltage values have been indicated merely by way of example. In this particular circuit, the tubes 13 and 14 were the two sections of a tube of the 6N7 type. 30 The tube 16 may be of a type having a characteristic similar to that of one section of the 6N7 tube.

As previously mentioned, the grid condenser-grid resistor circuits of the several tubes preferably have time constants of decreasing values. It has been found that this feature gives the overall circuit a better low frequency response.

As illustrated in Fig. 2, my invention is not limited to the use of the specific separating circuit shown in Fig. 1 but may comprise a first separating tube 41 having a cathode resistor 42 shunted by a condenser 43 for providing a variable grid bias due to plate current flow. The time constant of the biasing circuit 42-43 is such that most of the charge on condenser 43 holds over between successive frame synchronizing pulses. The synchronizing pulses, of course, are applied to the grid of the tube 41 with positive polarity.

50 The amplifier 44 may be the same as the amplifier 14 of Fig. 1. It will be understood, however, that in some instances it may be preferable to apply a fixed bias to the grid of either one of these amplifier tubes. It may be noted that the tube 44 (also the tube 14) acts as an amplifier rather than as a separator even though there is no fixed bias since substantially full plate voltage is applied.

The second separating circuit may be of the diode type comprising, for example, a diode 46 having a comparatively high resistance resistor 47 across which the signal is applied and a comparatively low impedance resistor 48 across which the synchronizing pulses only appear. The input signal is applied through a grid condenser 49 which is charged by the periodically recurring flow of diode current caused by the synchronizing pulses.

70 The discharge circuit for condenser 49 includes the resistor 47 which has a sufficiently high value to prevent the condenser 49 from discharging any great amount between the occurrence of successive line synchronizing pulses. This particular diode separator is described in Poch Patent 2,151,149, dated March 21, 1939.

It may be noted that, in the circuit of Fig. 1, it may be desirable in some cases to replace the particular second separating circuit shown by one of the diode type. As to the first separating circuit of the complete double separator combination, the particular type shown in Fig. 1 is generally preferred.

I claim as my invention:

1. In a television receiver wherein synchronizing pulses and picture signals are received as a composite signal in which said pulses are of greater amplitude than the picture signals, electric discharge tube means for separating said synchronizing pulses from said picture signals, an amplifier and a second electric discharge tube means for separating said pulses from said picture signals, said first means, said amplifier and said second means being connected in cascade in the order named.

2. In a television receiver wherein synchronizing impulses and picture signals are received as a composite signal in which said pulses are

of greater amplitude than said picture signals, a first means including a vacuum tube having a grid for separating said pulses from said picture signals when said composite signal is impressed upon said grid with sufficient amplitude and with the pulses of positive polarity, an amplifier tube, and a second means for separating said pulses from said positive signals, said first means, said amplifier, and said second means being connected in cascade in the order named.

3. The invention according to claim 2 characterized in that said amplifier tube is designed for working with approximately the same grid swing as is the vacuum tube of said first separating means.

4. The invention according to claim 2 wherein the vacuum tube of said first separating means has a grid condenser and a grid leak resistor with such relative values that said vacuum tube is grid-leak biased due to said pulses driving its grid periodically.

RANDALL C. BALLARD.
